(57) CLAIM

The ornamental design for a twistably actuated confectionery dispenser, as shown and described.

DESCRIPTION

1. Twistably actuated confectionery dispenser

1.1 : Perspective

1.2 : Top

1.3 : Bottom

1.4 : Front

1.5 : Back

1.6 : Left

1.7 : Right

1.8 : Exploded

A confectionery dispenser for amusement in the form of a bug-like alien featuring a caped body with arms and a head detachable from a cylindrical gel confectionery containing reservoir forming the torso and legs with an integrated twistable plunger shaped as feet.

1 Claim, 8 Drawing Sheets
